UNITED STATES PATENT OFFICE.

CHARLES R. WOOD, OF FARGO, NORTH DAKOTA.

POCKET FOR WEARING APPAREL.

Application filed January 7, 1922. Serial No. 527,635.

To all whom it may concern:

Be it known that I, CHARLES R. Wood, a citizen of the United States, residing at Fargo, in the county of Cass and State of North Dakota, have invented certain new and useful Improvements in Pockets for Wearing Apparel, of which the following is a specification, reference being had to the accompanying drawings.

10 It is well known that when garments, such as trousers are turned upside down, the contents of the pockets, such as keys, knives or loose change and the like fall out.

Therefore, the present invention has for 15 its purpose the provision of a pocket, wherein means is afforded for preventing the discharge of the contents of a pocket, when the trousers or like garment are inverted.

Another purpose is the provision of an 20 article of this kind, which may be termed a lock pocket, wherein means is afforded adjacent the pocket opening and upon opposite walls of the pocket, acting to retain the contents safely in the pocket and prevent them 25 from discharging, in case the trousers are inverted.

Still another purpose consists of a pocket 30 constructed substantially in the usual manner, including at least what may be termed as three locks on the walls of the pocket, particularly adjacent the pocket opening. For instance there may be one lock on one side, and two locks on the opposite side. It is also obvious that any number of locks 35 may be used, for instance two or possibly four, to insure the retention of the contents in the pocket.

A further purpose has to do with the construction of the locks, namely forming them 40 of extra pieces, which extend from the margin of the pocket opening, particularly adjacent to the walls of the pocket, and fastened to the far edge of the pocket, said extra pieces extending a substantial distance 45 down within the pocket, therefore in case the trousers should be inverted or turned upside down, the contents thereof, would no doubt, engage between these extra pieces, or what may be termed locks, and the walls of 50 the pocket, to insure the retention of the contents in the pocket.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts, as will be hereinafter set forth, shown in the drawings and claimed.

In the drawings:—

Figure 1 is a view of a portion of a garment, such as a pair of trousers or overalls, showing the pocket in dotted lines and constructed in accordance with the invention;

Figure 2 is a vertical sectional view on 70 line 2—2 of Figure 1, showing the opposite walls of the pocket proper, and also showing the lock walls, for causing the contents in the pocket to be retained therein;

Figure 3 is a transverse sectional view 75 through the pocket on line 3—3 of Figure 1, also showing the contents retaining lock walls, and illustrating how they are stitched together and to the walls of the pocket, in such wise as to prevent the discharge of the 80 contents;

Figure 4 is a plan view of the blank of the pocket;

Figure 5 illustrates collective views of the plurality of lock pieces or walls for the 85 pocket, to insure preventing the loss of the contents of the pocket;

Figure 6 is a detail perspective view of the pocket blank showing it folded; and

Figure 7 discloses collective perspective 90 views of the lock walls 3, 16 and 16^a ready to be inserted in place in the pocket blank 8.

Referring to the drawings, 1 designates a pair of trousers, overalls, or other garment, which is provided with a pocket opening 2. 95 The pocket adjacent the opening thereof includes a pocket lock wall 3 constructed of the same material of which the trousers or garment are constructed. This garment wall is stitched to the side seam of the trousers, 100 as at 4, and extends inwardly of the pocket a substantial distance as illustrated, in order

to constitute one lock wall for the pocket. The outer edge 6 of the pocket opening is folded inwardly of the pocket, and is stitched as at 7.

5 The pocket proper 8 is constructed of any suitable heavy durable fabric, such as used for pockets, and this material is cut as shown in the blank in Figure 4, and is folded upon line 9. The opposite walls 11 and 12 of the 10 pocket are stitched at their lower arcuate edges as at 13, and have their edge portions (which conform to the pocket opening), stitched to the edges of the pocket opening as at 14 and 15, (Figure 3).

15 Also stitched at 14 and 15 are pocket lock walls 16 and 16^a, which may be constructed of any suitable heavy durable material such as used for making pockets, and these lock walls extend inwardly and partly downwardly and parallel to the opposite walls of the 20 pocket are stitched as at 7, 14 and 15 to the opposite inner and outer walls of the pocket adjacent the opening thereof. The lock wall 16 conforms substantially to the inner pocket 25 wall, whereas the other lock wall 16^a conforms to the outer edge of the pocket opening, and is stitched to the outer edge portion of the pocket opening. The inner portions of the lock walls are stitched at 19 to the 30 inner wall of the pocket.

The lock walls act as suitable folds in the pocket, so arranged, as to prevent the discharge of the contents of the pocket, when the trousers in all instances are turned upside down or inverted.

35 The pocket lock wall 3 is stitched to the upper and lower parts of the inner lock wall 16, as indicated at 3^a and 3^b. The dotted lines *a* and *b* in Figures 5 and 7 show where the 40 pocket lock wall 3 is stitched or otherwise fastened at 3^a and 3^b, as in Figures 1, 2 and 3.

45 These seams or stitches 3^a and 3^b are very important in obtaining the safeness that is found in pockets of this character. For instance these stitches 3^a and 3^b are located sufficiently within the interior of the pocket, and are spaced sufficiently, the former above the latter to permit the insertion of the hand 50 of the wearer, in order to permit articles to be inserted in the pocket. Furthermore these stitches 3^a and 3^b are provided for the purpose of holding the contents retaining walls as close together and parallel as possible, and while said contents retaining walls are permitted to open sufficiently to permit the 55 insertion of the hand of the wearer, they will prevent the outward passage of the contents of the pocket, especially due to the particular location and arrangement of the stitches 3^a and 3^b, and also due to the walls being held together and in parallelism.

60 The invention having been set forth, what is claimed is:—

1. The combination with a garment hav-

ing a pocket, of contents retaining means 65 comprising a plurality of fabric walls arranged in parallelism and disposed in the pocket, certain of said contents retaining walls having upper inner stitched together edges, which are perpendicular to each other, 70 the lower edges of said plurality of contents retaining walls being stitched together and to the garment, the lower portions of two adjacent walls having a row of stitches connecting them, said row of stitches extending 75 inwardly and downwardly, the side edge of one of the remote contents retaining walls being stitched to the marginal edge of the pocket opening and to the garment, the corresponding edges of the other remote and adjacent contents retaining walls being stitched together and to the opposite margin of the pocket opening, and fastening means of triangular form connecting the upper portions of two of the contents retaining 80 walls.

2. The combination with a garment having a pocket, the opening to which being at the side of the garment, of three parallel fabric contents retaining walls disposed in 90 the pocket, the remote walls having upper inner parallel edges perpendicular to each other and fastened together, said remote walls having certain other of their edges fastened to the marginal edges of the pocket 95 opening, the intermediate wall having its corresponding edge fastened to one of the marginal edges of the pocket opening, the lower portions of all three contents retaining walls and the pocket walls being fastened together and to the garment, a fastener 100 connecting the lower portion of the intermediate wall and the lower portion of one of the remote walls, and extending angularly inwardly and downwardly; the upper 105 edges of all three walls being fastened together and to the upper part of the garment, fastening means connecting the intermediate wall and one of the remote walls, said last named fastening means extending downwardly and acting to prevent the loss of the 110 contents.

3. The combination with a garment having a pocket, the opening to which being at the side of the garment, of three parallel 115 fabric contents retaining walls disposed in the pocket, the remote walls thereof having upper inner edges perpendicular to each other and fastened together, said remote walls having certain other of their edges 120 fastened to the marginal edges of the pocket opening, the intermediate wall having its corresponding edge fastened to one of the marginal edges of the pocket opening, a fastener connecting the lower portion of the 125 intermediate wall and the lower portion of one of the remote walls and extending angularly inwardly and downwardly, the upper

edges of all three walls being fastened together and to the upper part of the garment, fastening means connecting the intermediate wall and one of the remote walls, 5 said last named fastening means extending downwardly and acting to prevent the loss of contents, said contents retaining walls

having inclined edges extending in the same general direction from the upper portion of the pocket to and adjacent the lower portion 10 of the pocket close to the pocket opening.

In testimony whereof I hereunto affix my signature.

CHAS. R. WOOD.
